UNITED STATES PATENT OFFICE.

DAVID W. SEGROVE, OF SPRINGFIELD, OHIO.

TUNING-FORK.

SPECIFICATION forming part of Letters Patent No. 329,090, dated October 27, 1885.

Application filed August 21, 1885. Serial No. 157,744. (Model.)

To all whom it may concern:

Be it known that I, DAVID W. SEGROVE, a citizen of the United States, residing at Springfield, in the county of Clark and State of Ohio, 5 have invented certain new and useful Improvements in Tuning-Forks, of which the following is a specification.

My invention relates to variable or adjustable tuning-forks; and the objects of my invention are, first, to provide a tuning-fork of ordinary or moderate size whereby sounds of any desired pitch may be produced, and, second, to provide a bridge or cross-bar of novel construction adapted to be readily adjusted to 15 the required position to obtain the desired pitch.

My invention consists in various constructions and combinations of parts, hereinafter described and claimed.

20 In the accompanying drawings, Figure 1 is a perspective view of a fork embodying my invention. Fig. 2 is a plan view of the same, showing the handle removed therefrom. Fig. 3 is a perspective view of the bridge or cross-bar in detail. Figs. 4 and 5 are views of a modified form of the bridge. Figs. 6 and 7 are views of the fork in different stages of construction, and Figs. 8 and 9 are views illustrating the manner of forming the bridge from 30 one piece of metal.

Like parts are indicated by similar letters of reference throughout the several views.

In the said drawings, A represents the fork proper; B, the adjustable bridge or cross-bar 35 therein, and C the handle, which is made separate from the fork, and preferably screwed therein.

The adjustable bridge B is adapted to slide between the prongs *aa* of the fork, and is held 40 therein by the spring or resilience of the said prongs. The prongs *aa* are provided with graduations corresponding to the different tones or semi-tones to be produced by the fork. In order that the bridge may be adjusted accurately at the mark or graduation to produce 45 a given tone, and also to hold the bridge from slipping transversely through the fork, I provide the said bridge on either side with projections *b b*, adapted to extend over the top of 50 the respective prongs, as shown. These pro-

jections serve as guides, or markers, whereby the exact graduation desired may be obtained.

To preserve the bridge at all times at right angles across the fork, and thus prevent the said bridge from being forced out by the elasticity of the prongs *aa*, pressing on the respective ends thereof, and at the same time to secure accuracy in the tone produced by the fork at a given graduation, I provide the bridge with backwardly-extending guides or projections *c*, 55 which extend from said bridge in close proximity to the prongs *aa*. These guides *c* I make in one piece of metal with the bridge B by first stamping the bridge out as shown in Fig. 8 and then shearing and forcing the projections *c* outward, as shown in Figs. 3 and 9.

It is obvious that the guides may be formed in different ways—as, for instance, as shown in Figs. 4 and 5, in which case the guides are made in a separate piece and riveted or otherwise secured to the bridge B.

In order to reduce the length and size of the fork to an ordinary or moderate size, and at the same time adapt the fork to secure a range of an octave in extent, I provide the prongs *a* 75 with enlarged or bell-shaped ends *e e*, the body of the prongs between the said enlarged ends and the base *e'* being made quite slender. The base *e'* is made heavier than the body of the prongs to secure the proper strength. 80

By making the handle C separate from the fork proper, as above stated, I am enabled to make the fork much more economically than could be done were the handle stamped out in one piece with the fork, as heretofore. In 85 constructing the fork I take a straight bar of steel, as shown in Fig. 6, cut to the proper length and of a size sufficient to form the width of the prongs and the enlarged ends thereof. This bar is then placed in a die and stamped 90 out to the shape shown in Fig. 7, after which it is bent into the form shown in Fig. 2 and the handle inserted therein. The handle is preferably turned up round and knurled on its outer surface, and is screwed or otherwise secured into the base *e'* of the fork proper.

In order to get a perfect bearing between the prongs *aa* and the bridge B, and thus secure a perfect tone in any position of adjustment which the bridge may occupy, I construct the ends of 95 100

said bridge slightly concave, so that a bearing or contact is secured only at the sides of the prongs. This not only secures a perfect contact at all times between said prongs and bridge, but also lessens the friction between 5 said parts, rendering the bridge very easily adjustable, and at the same time holds the bridge more firmly in its position. I have shown the concave ends of the bridge adapted 10 to bear against the inside of the prongs, though it is evident that the concave bearings may be used on the outside of the prongs with the same result.

It will be seen that by the construction above 15 described I secure a tuning-fork which may be readily adjusted to produce any tone within the octave, and by constructing the prongs of the shape described I am enabled to secure the adjustment necessary to produce an octave in 20 range without materially increasing the length beyond that of an ordinary non-adjustable or single-tone fork.

Having thus described my invention, I claim—

25 1. The combination, with a tuning-fork provided with graduations on the prongs thereof, of an adjustable bridge between said prongs, said bridge being provided with projecting ends adapted to mark the position of adjustment, substantially as set forth.

2. The combination, with the prongs of a tuning-fork, of a sliding bridge provided with concave ends adapted to form a bearing on each side of said prongs, substantially as set forth.

35 3. The combination, with the prongs of a tuning-fork, of a sliding bridge between said prongs and backwardly-projecting guides on said bridge, substantially as and for the purpose set forth.

4. The combination, with the prongs of a tuning-fork, of a sliding bridge therein provided with backwardly-projecting guides formed in one piece therewith, substantially as specified.

45 5. The combination, in a tuning-fork, with the adjustable sliding bridge, of the fork-prongs provided with the enlarged or bell-shaped ends, substantially as and for the purpose set forth.

50 6. The combination, with a tuning-fork, of a removable handle adapted to be secured to the base of said fork, substantially as specified.

7. The combination, with the fork the prongs of which are formed with enlarged or bell-shaped ends, of an adjustable bridge with concave ends and backwardly-projecting guides, substantially as set forth.

55 8. The combination, with a fork having graduated prongs, said prongs being provided with enlarged or bell-shaped ends, of an adjustable bridge provided with end projections adapted to extend over the said graduations and mark the position of said bridge, substantially as specified.

60 9. The combination, with a fork with prongs having enlarged or bell-shaped ends and enlarged base, of a separate or removable handle adapted to be secured in said base and an adjustable bridge in said prongs, substantially as set forth.

In testimony whereof I have hereunto set my hand this 2d day of March, A. D. 1885.

DAVID W. SEGROVE.
